E. J. HENRY.
WINDOW BED,
APPLICATION FILED JUNE 25, 1917.

Patented Apr. 15, 1919.

Ernest J. Henry
By J. M. & John
Atty.

UNITED STATES PATENT OFFICE.

ERNEST J. HENRY, OF CEDAR RAPIDS, IOWA.

WINDOW-BED.

1,300,266.

Specification of Letters Patent. Patented Apr. 15, 1919.

Application filed June 25, 1917. Serial No. 176,883.

To all whom it may concern:

Be it known that I, ERNEST J. HENRY, a citizen of the United States, residing at Cedar Rapids, in the county of Linn and State of Iowa, have invented certain new and useful Improvements in Window-Beds; and I do hereby declare the following to be a full, clear, and exact description of the invention, such as will enable others skilled in the art to which it appertains to make and use the same.

The object of this invention is to produce a window-bed adapted for adjustment to windows of varying size, and transportable from room to room; which is so constructed and mounted as to be perfectly safe when thrust through the window to sleeping position; is easily manipulated by the user; may be rendered weather-proof, as well as proof against flies and mosquitos, and may be regulated by the drawing of curtains so as to perfectly control the admission of light and air.

The nature of the invention is fully disclosed in the description and claims following, reference being had to the accompanying drawing, in which:

Figure 1 is a side view of my improved window-bed in sleeping position, the most of the fly-netting being broken away the better to show parts inside it. Fig. 2 is a cross section of the same in the line a^2-a^2 , looking to the left. Fig. 3 is a similar view in the line a^3-a^3 . Fig. 4 is a top view in perspective showing details of a supporting flap to bear against the bottom rail of the lower sash. Fig. 5 is a sectional plan view, showing details of one of the side wings which bear against the window casing. Fig. 6 shows a modification in the bracing of the same. Fig. 7 is a sectional plan view, showing details of a bracket support attached to the bed frame and adapted to bear on the edge of the window sill. Fig. 8 is a side view of the same. Fig. 9 is a view in perspective showing details of the mounting of the bed frame on supporting stools or pedestals and means for locking the parts together. Fig. 10 shows in perspective a simple closure for an opening each side of the bed rails. Fig. 11 shows similarly a closure for an opening above the wings, both closures being for the purpose of excluding flies and mosquitos.

In the drawing, the numeral 1 denotes a

portion of the wall of a building, in section, and the line 2, the floor. 3 indicates the lower sash of a window, and 4, the window casing, all of which are of familiar construction. A simple type of bed-frame is shown, the side-rails 5 being formed of channel-steel, with head and foot cross-bars 6, to which is here indicated a woven wire spring 7 as being attached in a well known way. The bed frame is supported on suitable legs, which are herein shown as independently standing stools or pedestals 8, each having four legs. These legs are made adjustable as to height by internally threading the main legs and inserting therein externally threaded extension legs 9. These may be screwed up or down as desired, and fastened by thumb-screws 10, to bring the bed to the proper level with respect to the window-sill 11, the heights of which vary in different houses. The bed-frame is slidable on these pedestals, the device for that purpose herein shown being rollers 12 mounted on brackets 13, attached to the tops of the pedestals, the rollers traveling in the channels of the bed-frames. Ordinarily that at the foot of the bed is locked in position, a simple dog 14, notched at 15, and pivoted to the bed-frame, serving to engage the top of one of the roller brackets. It is to be understood that the head pedestal is locked in the same way. By means of the tail-piece 16 either dog is disengaged to move the bed along the supports, or remove it wholly therefrom, as is sometimes necessary, as in storing the bed when not in use, or moving it from room to room through doors narrower than the bed.

The head half of the bed is provided with a canopy to serve as a protection and screen for the occupant. This consists mainly of corner posts 17 suitably secured to the bed-rails, as by corner plates 18; top-plates 19, and a pitched roof 20 composed of a central ridge 21, small rafters 22 and a suitable water-proof covering, such as oil-cloth 23, or the like. On the three outer sides the canopy is inclosed with wire netting 24. At the open sides and end are hung water-proof shades 25 and 26, the former, which is the outer one, being of solid material, and the inner one being provided with apertures at a little distance above the bottom edge, as shown at 27. These serve to conceal the sleeper from observation, while freely ad-

mitting air to the inclosure. Provision is also made for the hanging of draperies, as shown by the curtain-rod 28 in Fig. 2, it being understood that these may be placed 5 at the sides as well as at the end. At the edges the outer shades are overlapped by thin weather-strips 29 secured to the posts, the strips being adapted to exclude wind and rain. Bars 35 prevent accidental falling out of bed.

At the front end of the canopy are abutments 30, projecting sidewise to bear on the inner faces of the window casing, and hold the bed securely in position. When the 15 bed is made specifically for a window these abutments may be attached to, or form parts of the inner posts, of the canopy as above described. But as there is great variation in the width of windows, I have provided 20 for the use of wide abutments, serving for wide as well as narrow windows, and foldable against the sides of the bed so as to admit of its being taken through ordinary doors. These abutments, or wings, are pivoted like doors somewhat forward of the 25 inner posts, and swing back toward the foot of the bed, at right angles thereto, where they are held rigidly by braces 31. If made of wood, the wings should be provided with 30 end-strips of steel 32, the channel-steel shown in Fig. 10 being preferred. The wings are pivoted to the bed-frame at the lower ends, and at the upper ends to a header 33 projecting footward from the 35 canopy. Adjacent to the wings are supplemental posts 34, serving mainly as supports for the inner edges of the wire screen, which takes the offset course shown in Fig. 40, leaving a recess into which the wing may fold when not in use. This brings the outer face of the wing flush with the outer side of the bed, and gives no extra projection 45 to interfere with openings that are as wide as the bed, and but little wider. A simple strut, hinged to the bed-rail, and abutting against a lug 36, is shown in Fig. 5. The preferred construction is shown in Fig. 6, the strut being hinged to a T 37 sliding in a slot 38 formed in the channel-bar and in a 50 pocket rabbeted in the wing.

To the header is attached another abutment, heretofore referred to as a flap, 39. This, as will be seen, stands upright when in use, and bears against the inner face of 55 the bottom rail of the window sash. When not in use it may be folded down, so that it occupies but little space, and in case the bed is wider than the height of the canopy, would allow for the passage of the bed 60 through a narrow door, by turning the bed up edgewise. As the position of window-sash in relation to the inner face of the window casing varies greatly, this flap is 65 made adjustable, a simple device for the purpose being shown in Fig. 4. Here the

lower leaves of the hinges 40 are set in rabbeted grooves 41, and are fastened by suitable screw-bolts 42 in slots 43.

An auxiliary support for the outer portion of the bed and canopy is shown in Figs. 1, 7 and 8. This is a triangular bracket-plate 44 hinged at 45 to a slotted support 45^a attached to the bed-rail, it being understood that there is one for each side of the bed. The bracket swings on a pivot-bolt 45 which is shouldered at 46, the reduced and threaded portion passing through the slot and a washer 47, and is secured by a nut 48. The adjoining faces of the slotted plate and the washer are serrated to prevent slippage. 80 When set to the proper position the bracket may be swung over to bear on the upper, outer angle of the window-sill, which it engages with a wedging action, and thus serves to support the canopy portion of the bed 85 very securely and safely. As window-sills differ very largely in width I have shown a double adjustment, extra pivot-holes in the bracket-plate, as well as the slot.

Referring to Fig. 3 it will be seen that 90 the insertion of the bed in a large window opening leaves four openings to be barred against insects. Those at the bottom of the window, 49, are closed in a very simple way, by hanging a sheet of thin metal, 50, by one 95 corner, so that it may be turned to position to close the opening, or turned back, when not in use. The openings 51 are closed by means of slides of sheet metal, slotted at 52 for sliding attachment, as by screws 53, 100 to the header, and flanged at 54 corresponding to the thickness of said header. The outer edge of the slide abuts against the window-sash (or might lie under it), and the end of the slide adjacent to the sash 105 needs to be clipped to fit neatly against the inner window stop. In practice this slide is made wide enough to reach the sash in deep window frames, and for shallower ones would be trimmed to fit. It is moved 110 by knobs 55.

As above indicated, the aim in devising the window bed described has been to render it as adaptable as possible to residences, 115 hotels, and other houses, so that with a comparatively few stock sizes it will be possible to fit a large range of sizes and shapes of windows. It is also readily portable, there being practically no projections beyond the essential bodies of the bed and canopy to 120 interfere with its passage through doors or other openings. It is to be noted also that the equipment of the canopy and other parts is such as to be accessible and easily operated by the occupant of the bed.

Having thus described my invention, I 125 claim:

1. In a window-bed, the combination of a bed-frame, an attached canopy, rigid, up-standing wings hinged to the sides of the 130

canopy at the inner end, and braces to hold said wings at right angles to the canopy, substantially as described.

2. In a window-bed, the combination of a bed-frame, a canopy attached thereto, rigid, upstanding wings hinged to the sides of the canopy at the inner end, braces to hold said wings at right angles to the canopy, and a rigid, horizontal flap hinged to the top of the canopy near the inner end, the side wings serving as closures and abutments at the sides of the canopy, by overlapping the window casing, and the top flap abutting the lower rail of the raised sash.

15 3. In a window-bed, the combination of a bed-frame, a canopy attached thereto, foldable wings adjacent to the inner end of the canopy, an adjacent post, and screen wire inclosing the canopy and passed behind said wings and attached to said post, leaving a recess into which the wing may fold when not in use.

4. In a window-bed, the combination of a bed-frame, a canopy attached thereto, having an inwardly projecting inner header for the window sash to rest upon, an adjustable, folding flap hinged to said header, and adapted to form an inner support for the canopy by abutting against said sash.

30 5. In a window-bed, the combination of a bed-frame, a canopy attached thereto, folding wings adjacent to the inner end of the canopy and adapted to fold flush with the sides thereof when not in use, and braces adapted to hold the wings rigidly at right angles to the bed-frame.

6. In a window-bed, the combination of a bed frame having longitudinally grooved rails, and a pair of independent, self-supporting pedestals provided with rollers to travel in said grooved rails independently, whereby the pedestals may be set at any de-

sired position with respect to the bed, or entirely removed therefrom.

7. In a window-bed, the combination of a 45 bed-frame having longitudinally grooved rails, pedestals independently and slidably mounted therein, and locking dogs to fasten the bed to the pedestals.

8. In a window-bed having a closed canopy 50 with lateral abutments at its inner end to bear against the window-casing, brackets hinged to the bed inside said canopy, whereby they may be manipulated by the occupant of the bed from within the canopy, as described.

9. In a window-bed, the combination of a bed-frame, a canopy therefor, folding side wings to abut against the window-casing, and swinging plates adapted to close the 60 openings below the wings and at the sides of the frame.

10. In a window-bed, the combination of a bed-frame, a canopy therefor having a header for the window sash to close upon, 65 an abutment flap to bear against the inner face of the sash, and slide-plates adjustably mounted at the ends of the header, to close the openings between said ends and the adjacent window-frame.

11. In a window-bed, the combination of a bed-frame, a canopy attached thereto, with means to hold the bed partly projected through a window, and supporting pedestals independently and slidably attached to the 75 bed-frame, and vertically adjustable, substantially as and for the purpose set forth.

In testimony whereof I affix my signature in presence of two witnesses.

ERNEST J. HENRY.
